CLAIM

The ornamental design for an aircraft seat partition, as shown and described.

DESCRIPTION

FIG. 1 is a perspective view of an aircraft seat partition showing our new design;

FIG. 2 is a front elevational view thereof;

FIG. 3 is a rear elevational view thereof;

FIG. 4 is a left side elevational view thereof, a right side elevational view thereof being a mirror image of the left side elevational view thereof;

FIG. 5 is a top plan view thereof; and,

FIG. 6 is a bottom plan view thereof.

The portions indicated in broken lines are for illustrative purposes only and form no part of the claimed design.
